United States Patent Office.

SIDNEY C. TREAT, OF TABOR, IOWA, ASSIGNOR TO HIMSELF AND CHARLES P. TREAT, OF OBERLIN, OHIO.

Letters Patent No. 102,883, dated May 10, 1870.

IMPROVEMENT IN LIQUID-METERS.

The Schedule referred to in these Letters Patent and making part of the same.

To all whom it may concern:

Be it known that I, SIDNEY C. TREAT, of Tabor, county of Fremont, in the State of Iowa, have invented a new and improved Liquid-Meter; and I do hereby declare that the following is a full and exact description thereof, reference being had to the accompanying drawings and to the letters of reference marked thereon.

Figure 1 is a side view.

Figure 2 is a top or plan.

Figure 3 is a longitudinal section.

Figure 4 is a detached section of valve.

The nature of this invention relates to the construction of a machine for measuring the flow or passage of water by means of a cylinder having a piston, the reciprocatory motion of which works a registering-device.

This invention consists especially in the construction and operation of the valve through which the liquid passes.

In the drawings—

A represents a cylinder, mounted on a suitable frame, B, in which cylinder plays a piston, acted upon by the water conducted into the cylinder at each end, through the pipes b c.

In the frame or bed B is placed a valve, C.

This valve, comprising the principles in this invention, is constructed as follows:

A round valve-chamber, c, is provided, having in the bottom four ports, e¹ e² e³ e⁴.

The first port e¹ is the inlet-port.

The ports e² and e³ connect with the pipes b c, leading to either end of the cylinder, e⁴ being the discharge-port.

The valve consists of a disk, d, having a circular groove, d', in its under side, long enough to cover and connect two of the ports.

Opposite to this groove is a circular slot, d'', also long enough to connect two of the ports.

This slot is intended to permit the water to fill the valve-chamber above the valve, so as to equalize the pressure upon the valve, the pressure upon the top keeping the valve close down upon its seat.

The top of the valve-chamber is covered by a cap or cover, f, through which cover extends the valve-stem, g, which valve-stem is attached to the valve by being set loosely in a hole in the neck of the valve, there being made two small slots i i in the neck of the valve, in which pins rest. This is to provide against the valve being disturbed from its seat in case of any jarring or lateral motion of the valve-stem.

There is a frame, D, attached to the frame or bed B, which is placed over the valve, and in which the upper end of the valve-stem rests and turns.

The frame D is provided with ways h h, in which a frame, E, attached to the piston-rod F, slides.

A sleeve, k, having two arms or levers, k' k'', is placed loosely on the valve-stem g, resting upon a shoulder, g', of the stem.

The lever k' is connected to the frame E by the pitman l.

Secured to the valve-stem g is a lever, m, which has two dogs, n n', pivoted at its outer end.

These dogs are held down by a spring, n''.

Two springs p p are provided, one end of each being attached to the sleeve k, and the other end to the lever m, which, by their tension, will cause the lever m to fly around quickly when set at liberty.

Across the bed B is placed a circular way, o, having a notch at each end, into which the dogs catch alternately, holding the lever m in place until released by the levers k' or k'' striking against the dogs, when they are raised, and, releasing their hold, the springs force the lever around quickly, making a quarter turn, the valve being thus changed, the ports e¹ and e⁴ being alternately covered and uncovered by the grooves d' and d''.

It will be observed by this arrangement the water passes (as seen in fig. 4) in the direction of the arrows, first through the port e¹ into the chamber c, thence into the port e², and on into the cylinder, through the pipe b, forcing the piston forward, and when it arrives near the end, the lever k'' arrives at and strikes the dog n', raising it, releases the lever m, which quickly flies around, changing the valve so that the slot covers the ports e¹ and e⁴, and the groove covers the ports e² and e³, permitting the water to pass into the pipe c, when a reverse motion is made by the piston, the water discharging through the port e⁴.

Having thus described my invention,

What I desire to secure by Letters Patent is—

1. The valve C, having the groove d' and slot d'' seated in the valve-chamber c, and covering the ports, as shown and for the purpose described.

2. The combination with the valve-stem g, the lever m, provided with the dogs n n', the sleeve k having the levers k' k'', the springs p p attached to the sleeve k and lever m, for actuating the lever m, the pitman l for connecting the lever k with the frame E, the circular way o upon which the dogs slide and catch as shown, the whole being constructed, arranged, and operating upon the valve d as shown, and for the purpose set forth and described.
